C. W. KECKLER.
TELEPHONE EXCHANGE SYSTEM.
APPLICATION FILED OCT. 30, 1917.

1,419,569.

Patented June 13, 1922.

UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,419,569.

Specification of Letters Patent. Patented June 13, 1922.

Application filed October 30, 1917. Serial No. 199,235.

To all whom it may concern:

Be it known that I, CHARLES W. KECKLER, a citizen of the United States, residing at Newark, in the county of Essex and State of 5 New Jersey, have invented certain new and useful Improvements in Telephone-Exchange Systems, of which the following is a full, clear, concise, and exact description.

This invention relates to telephone exchange systems, and more particularly to such systems of the central energy type. The object of this invention is to provide improved signaling means for systems of this character.

15 In accordance with this invention there is provided a trunk circuit extending between operators' positions which is equipped with apparatus by means of which, when the incoming end thereof is connected with a telephone line to which a cord circuit or another trunk circuit is connected, the supervisory signaling device in a cord circuit connected with the other end thereof is caused to operate intermittently to indicate to the operator that the trunk circuit has been connected with a busy line. Upon the disconnection of the cord or trunk circuit which has rendered the line busy, apparatus in the second trunk circuit is rendered effective to cause the continuous operation of the supervisory signaling device to indicate to the operator that the called-for line may be now signaled.

For a more complete understanding of this invention reference is to be had to the 35 following description considered in connection with the accompanying drawing illustrating one embodiment of this invention.

There are shown in the drawing two telephone lines A and B, which terminate at 40 different operators' positions. The line circuit A may be connected with a cord circuit C in any desired manner. The cord circuit C and the line B may be joined together by means of a trunk circuit D. The apparatus 45 shown to the left of the dotted line 2-2 is at the originating operator's position X and that to the right of this line is at the terminating or trunk operator's position Y. It is to be understood that a plurality of 50 lines similar to A and a plurality of cord and trunk circuits similar to C and D may be provided, but for the sake of convenience, only the two lines and one cord and one trunk circuit are shown in the drawing.

55 Assuming that after subscriber A is connected with the cord circuit the operator learns that connection is desired with the line of subscriber B, the operator at position X communicates with the operator at position Y over an order wire circuit (not shown), whereupon the distant or trunk operator will assign the trunk circuit to be used. It will be assumed that trunk circuit D has been assigned. The originating operator thereupon inserts plug 5 into jack 6, whereupon relay 7 of the trunk circuit and relay 8 of the cord circuit C are operated over a circuit from battery through the lower winding of relay 7, lower normal contact of relay 9, tip contacts of the jack 6 and plug 5, winding of relay 8, ring contacts of the plug 5 and jack 6, upper normal contact of relay 9 and upper winding of relay 7 to ground. Relay 7, in operating, causes lamp 10, associated with the incoming end of the trunk circuit D, to be lighted over a circuit from battery through the lamp 10, lower normal contact of relay 11 and alternate contact of relay 7 to ground. The operation of relay 8 causes supervisory lamp 12 to be 70 lighted. If the line B is busy when the incoming end of the trunk circuit D is connected therewith, the lamp 12 will be caused to glow intermittently; while, if the line is not busy when connection is made therewith, the lamp 12 will glow continuously to serve as a ringing signal. The trunk operator upon observing the lighted condition of lamp 10, indicating that connection has been made with the assigned trunk circuit, 75 immediately inserts plug 15 thereof in jack 16 of line B. Relay 17 is thereupon operated in series with cut-off relay 18. Relay 17 in operating causes the operation of relay 11, thereby opening the circuit of lamp 10, extinguishing the lamp. If, when plug 15 is inserted in the jack 16, a cord circuit or another circuit similar to D is connected with jack 19 of line B, battery is then connected through the ring strand of the previously connected cord or trunk circuit to the ring contact of jack 19, so that upon the insertion of the plug 15 into jack 16 relay 20 operates. The operating circuit for this relay 20 is from battery in the cord or trunk 80 circuit connected with jack 19, over the ring strand and contact thereof, ring contacts of jack 16 and plug 15, right-hand normal contact of relay 21 and the right-hand winding of relay 20 to ground. Relay 20, in operat-

110

ing, opens its normal and closes its alternate contacts. The closure of the right-hand alternate contact causes the operation of relay 22 over a circuit from battery through the 5 contact of relay 17, right-hand alternate contact of relay 20, and the winding of relay 22 to ground. Relay 22 in operating completes a locking circuit for itself through its left-hand contact and prepares at its right-hand 10 contact a circuit for relay 21. The closure of the left-hand alternate contact of relay 20 connects an interrupter 23 in circuit with the upper winding of relay 9, thereby causing the intermittent operation of this relay 15 9. In the intermittent operation of relay 9, contacts in circuit with supervisory relay 8 of cord circuit C are alternately opened and closed, thereby causing the alternate de-energization and energization of relay 8, 20 which results in the intermittent lighting 25 of the supervisory lamp 12. This intermittent glowing of lamp 12 serves as the signal to the originating operator that the incoming end of the trunk circuit D has been connected with a busy line. Relay 9, in opening 30 its normal contacts which are in circuit with the windings of relay 7, does not permit this relay 7 to be released, for the closure of the alternate contact of relay 9 establishes a holding circuit through the lower winding of relay 7, thereby maintaining it 35 energized. As long as the plug 15 remains connected with the jack 16, while another cord or trunk circuit is connected with an other jack thereof, the supervisory lamp 12 will be lighted intermittently. The calling 40 subscriber may thereupon be advised that the wanted line is busy, and, if the calling party so desires, the connection may remain 45 set up as a waiting connection until the cord or trunk circuit rendering the line B busy is disconnected, when the lamp 12 will glow 50 continuously to serve as a ringing signal to the originating operator. It will also be ob- 55 served that even if the originating operator should actuate the ringing key 30 while the trunk circuit is connected with a busy line, the source of ringing current 35 cannot be connected therewith, for the ring strand is 60 open at the alternate contact of relay 21.

When the trunk or cord circuit which has rendered line B busy is disconnected from the jack of line B, the circuit through the right-hand winding of relay 20 is opened at the 65 jack contact. When relay 11 was operated as before described a circuit was completed from battery through interrupter 25, left-hand normal contact of relay 21, left-hand winding of relay 20, and the middle alternate contact of relay 11 to ground. An intermittent energizing circuit was thereupon completed for relay 20. If this energizing circuit including the interrupter 25 is closed at the time the circuit through the right-hand winding of relay 20 is interrupted, 70 relay 20 will be maintained energized until interrupter 25 reaches an insulating segment, thereby opening the circuit through the left-hand winding of relay 20. Relay 20 thereupon immediately releases its armatures, disconnecting interrupter 23 from circuit relation with relay 9 and stopping the intermittent lighting of the supervisory lamp 12. Relay 8 of the cord circuit C will remain 75 energized, causing the lamp 12 to glow continuously to indicate a ringing signal to the originating operator. The closure of the right-hand normal contact of relay 20 causes the operation of relay 21 over a circuit from battery through the contact of relay 17, normal contact of relay 20, winding of relay 21 and the right-hand contact of relay 22 to ground. Relay 21, in operating, introduces a break in the circuit including the interrupter 25 and the left-hand winding 80 of relay 20, and by the opening of its right-hand normal contact introduces another break in the circuit including the right-hand winding of relay 20. The closure of the alternate contact of relay 21 closes the normally open ring strand of the trunk circuit D. The originating operator noting the change in the character of the signal given by the supervisory lamp 12, knows that she may now signal subscriber B. This is done 85 by actuating ringing key 30, whereupon relay 32 of the trunk circuit is operated by current from the source of ringing current 33. Relay 32 in operating causes the operation of a ringing relay 34 over a circuit from battery through the contact of relay 32, winding of relay 34, and lower winding of relay 9 to ground. Relay 34 in operating connects the source of ringing current 35 with the line B to cause the operation of the usual call bell at station B. During the time that the ringing key 30 is operated, relay 9 is energized, thereby causing the de-energization of supervisory relay 8 so that the lamp 12 will be extinguished while the 90 operator is signaling the wanted line. The ringing key 30 upon being restored to normal position causes the release of relays 9 and 34 and the operation of relay 8, thereby 95 relighting the supervisory lamp 12. The 100 called subscriber B in responding to the operation of the call bell removes the receiver from the switchhook, thereby causing the operation of the supervisory relay 36. In operating relay 36 causes the energization of relay 9 over a circuit from battery through the contact of supervisory relay 36, left-hand normal contact of relay 20, the upper winding of relay 9 and alternate contact of relay 7 to ground. Relay 9 in operating causes 105 the release of relay 8, thereby extinguishing the supervisory lamp 12, which indicates to the originating operator that the called party has answered. 110

At the conclusion of the conversation the 115 120 125 130

subscribers restore the receivers to the signal, and means responsive to the disconnection of the first trunk circuit from the line to cause the signaling device to furnish a continuous signal.

- 5 5 lay 9, and the energization of supervisory relay 8, whereupon supervisory lamp 12 is lighted to furnish a disconnect signal. The originating operator may thereupon remove the plug 5 from the jack 6, whereupon relay 10 7 releases its armature, completing a circuit for, and causing the lighting of, the lamp 10. This circuit may be traced from battery through the lamp 10, lower alternate contact of relay 11, and the normal contact of relay 15 7 to ground. The trunk operator observing the lighted condition of lamp 10, which serves as a disconnect signal, may withdraw the plug 15 from the jack 16, whereupon all apparatus is restored to normal condition.
- 20 If when the plug 15 is inserted in the jack 16 no other cord or trunk circuit is connected with another jack of line B, no circuit will be completed through the right-hand winding of relay 20, but when the conducting segment of interrupter 25 bridges the brushes thereof, a circuit is completed through the left-hand winding of relay 20, so that it attracts its armatures, causing the energization and locking up of relay 22. The length of 25 time that the brushes of interrupter 25 are bridged by the conducting segment thereof is not sufficient to cause the intermittent lighting of the supervisory lamp 12. Upon the subsequent engagement of the insulating segments of interrupter 25 with the brushes thereof, relay 20 is released as hereinbefore described, thereby completing the circuit of relay 21. From this point on, the operation is as before described.
- 30 40 From the above description it will be apparent that by utilizing the applicant's invention in telephone systems a positive signaling means is provided, by means of which the originating operator may be advised of the progress in setting up connections between subscribers. By utilizing applicant's invention a very simple signaling scheme is provided for use in telephone systems where it is desirable to establish waiting connections.
- 50 What is claimed is:
1. A telephone exchange system comprising a telephone line terminating at a switchboard section, a plurality of trunk circuits extending therefrom to a second section, one of said trunk circuits being connected to the telephone line, a link circuit at the second section connected with another of the trunk circuits, a signaling device in the link circuit, a relay operated irrespective of the operation of any other apparatus in the trunk circuit of which said relay forms a part due to the connection of a second trunk circuit with the telephone line to cause the signaling device to furnish an intermittent
2. A telephone exchange system comprising a telephone line, a link circuit connected with the line, a second link circuit comprising a normally open talking strand, a signaling device, and a relay normally connected with the talking strand and initially energized thereover upon connection of the second link circuit with the telephone line, interrupter mechanism brought into operative relation with the signaling device by the operation of the relay to cause the intermittent operation thereof, circuit connections rendered effective upon the disconnection of the first link circuit from the line for causing the continuous operation of the signaling device, and a relay also responsive to the disconnection of the first link circuit from the line for disconnecting the first mentioned relay from the talking strand and closing the talking strand.
3. A telephone exchange system comprising a telephone line terminating at a switchboard section, a plurality of trunk circuits extending therefrom to a second section, one of the trunk circuits being connected with the telephone line, talking conductors therefor, a link circuit at the second section connected with another of the trunk circuits, a signaling device in the link circuit, interrupter mechanism, an electromagnetic switching device energized over a path including a portion of the talking conductor and irrespective of the operation of any other apparatus in the trunk circuit of which said switching device forms a part due to the connection of the second trunk circuit with the telephone line to operatively associate the signal device and interrupter mechanism whereby the signaling device is intermittently operated, and circuit connections rendered effective upon the disconnection of the first trunk circuit from the line to cause the continuous operation of the signal device.
4. A telephone exchange system comprising a telephone line terminating at a switchboard section, a plurality of trunk circuits extending therefrom to a second section, one of the trunk circuits being connected to a telephone line, talking conductors therefor, a link circuit at the second section connected with another of the trunk circuits, a relay in the link circuit bridged across the talking circuit thereof, a signaling device at the second section controlled by the link circuit relay, a relay in the second trunk circuit energized over a path including a portion of the talking conductor and irrespective of the operation of any other apparatus in the trunk circuit of which said relay forms a part due to the connection thereof

41. with the telephone line, and an interrupter operatively associated with the talking circuit of the connected link and trunk circuits by the operation of the trunk relay to cause 5 the intermittent energization of the link circuit relay whereby the signaling device is intermittently operated, said trunk relay being deenergized upon the disconnection of the first trunk circuit from the telephone line to 10 discontinue the operative association of the interrupter and said talking circuit whereby the signaling device is continuously operated.

5. A telephone exchange system, comprising 15 a telephone line terminating at a switch-board section, a plurality of trunk circuits extending therefrom to a second section, one of the trunk circuits being connected with the telephone line, talking conductors there- 20 for, a link circuit at the second section connected with another of the trunk circuits, two relays energized upon the connection of the second trunk circuit with the line, one over a local circuit, the other over a path 25 including a portion of the talking conductor and irrespective of the operation of any other apparatus in the trunk circuit of which said relay forms a part, a third relay operated upon the energization of the two relays 30 and thereafter rendered independent of the talking circuit relay, and a fourth relay energized upon the deenergization of the talking circuit relay to disconnect the talking circuit relay from the talking conductor.

35. 6. A telephone exchange system comprising 35 a telephone line terminating at a switch-board section, a plurality of trunk circuits extending therefrom to a second section, one of said trunk circuits being telephonically connected with the telephone line, a link circuit at the second section connected with another of the trunk circuits, a signaling device in the link circuit, a relay operated irrespective of the operation of any other apparatus due to the connection of the second 40 trunk circuit with the telephone line to cause the signaling device to furnish an intermittent signal, and means responsive to the disconnection of the first trunk circuit 45 from the line to cause the signaling device to furnish a continuous signal.

50. 7. A telephone exchange system comprising 50 a telephone line terminating at a switch-board section, a plurality of trunk circuits extending therefrom to a second section, one of the trunk circuits being telephonically connected with the telephone line, talking conductors therefor, a link circuit at the second section connected with another of the 55 trunk circuits, a signaling device in the link circuit, interrupter mechanism, an electromagnetic switching device energized over a path including a portion of the talking con-

ductor and irrespective of the operation of any other apparatus due to the connection 65 of the second trunk circuit with the telephone line to operatively associate the signal device and interrupter mechanism whereby the signaling device is intermittently operated, and circuit connections rendered effective upon the disconnection of the first 70 trunk circuit from the line to cause the continuous operation of the signaling device.

8. A telephone exchange system comprising 75 a telephone line terminating at a switch-board section, a plurality of trunk circuits extending therefrom to a second section, one of the trunk circuits being telephonically connected to a telephone line, talking conductors therefor, a link circuit at the second 80 section, connected with another of the trunk circuits, a relay in the link circuit bridged across the talking circuit thereof, a signaling device at the second section controlled by the link circuit relay, a relay in the sec- 85 ond trunk circuit energized over a path including a portion of the talking conductor and irrespective of the operation of any other apparatus due to the connection there- 90 of with the telephone line, and an inter- 95 rupter operatively associated with the talking circuit of the connected link and trunk circuits by the operation of the trunk relay to cause the intermittent energization of the link circuit relay whereby the signaling de- 100 vice is intermittently operated, said trunk relay being deenergized upon the disconnection of the first trunk circuit from the telephone line to discontinue the operative association of the interrupter and said talking circuit whereby the signaling device is continuously operated.

9. A telephone exchange system, comprising 105 a telephone line terminating at a switch-board section, a plurality of trunk circuits extending therefrom to a second section, one of the trunk circuits being telephonically connected with the telephone line, talking conductors therefor, a link circuit at the sec- 110 ond section connected with another of the trunk circuits, two relays energized upon the connection of the second trunk circuit with the line, one over a local circuit, the other over a path including a portion of the talking 115 conductor and irrespective of the operation of any other apparatus, a third relay operated upon the energization of the two relays and thereafter rendered independent of the talking circuit relay, and a fourth re- 120 lay energized upon the deenergization of the talking circuit relay to disconnect the talking circuit relay from the talking conductor.

In witness whereof, I hereunto subscribe my name this 26th day of October A. D., 1917.

CHARLES W. KECKLER.
